(57) **CLAIM**

The ornamental design for a combined nipple and collar, as shown and described.

DESCRIPTION

FIG. 1 is a side elevational view of a combined nipple and collar showing my new design.

FIG. 2 is a top plan view of the combined nipple and collar.

FIG. 3 is a bottom plan view of the combined nipple and collar; and,

FIG. 4 is a perspective view of the combined nipple and collar.

The broken line showing of the bottle in FIG. 4 is for illustrative purposes only and forms no part of the claimed design.
